WRITING INSTRUMENT

Ernest H. Seibert and Joseph J. Cada, Chicago, Ill., assignors to Cory Corporation, Chicago, Ill., a corporation of Delaware

Application May 21, 1953, Serial No. 356,506

6 Claims. (Cl. 120—42.03)

The present invention relates to writing instruments and more particularly to a novel ball point pen or writing instrument in which the writing point is readily moved or propelled to writing position, or moved to retracted position within the barrel.

Writing instruments of the ball point type that are now commercially available are either of the type in which the writing point is not retractable and a removable cap is provided for covering and protecting the writing point when not in use, or of the retractable type in which the removable cap is dispensed with and means are provided for retracting the point to inoperative position when not in use.

The present invention relates to the type of writing instrument in which the ball or writing point is retractable, but in which the actuating push button or the like of the prior pens or instruments has been eliminated and novel means and mechanism have been provided for propelling the writing point to writing or operative position and for retracting or withdrawing this writing point to inoperative position within the protection of the barrel when not in use.

It is, therefore, an important object of the present invention to provide a novel writing instrument or ball point pen of the retractable type.

It is a further object of the present invention to provide a novel writing instrument or ball point pen in which the ball or writing point is moved or propelled to exposed writing position by a novel cap and plunger assembly, and automatically held latched in such writing position, and in which the writing point is automatically retracted upon releasing and unlatching the plunger.

The present invention further comprehends the provision of a novel writing instrument having a retractable ball point that may be quickly and effectively retracted into the barrel upon depressing the pocket clip and actuating a release bar.

Another object of the present invention is the provision of a novel ball point pen or writing instrument having mechanism for moving the ball or writing point to exposed or writing position by merely depressing or moving a cap shell or member relative to the barrel assembly, and releasing this mechanism for retracting or returning the ball or writing point to inoperative and protected position by merely actuating the free or pocket engaging end of the clip. The means for propelling the writing point and the means for retracting the same are so constructed, arranged and related that the probability of the user returning the pen with its ball or writing point to his pocket or place of storage after use exposed is indeed remote. In fact, to return the pen to the pocket and its retention by the clip automatically depresses the release bar and disengages the latching means whereby retraction of the writing point is assured.

A still further object of the present invention is the provision of novel actuating means for propelling and repelling or retracting the writing point of a pen in a most effective, positive and novel manner and without an exposed push button or other means projecting from the body of the instrument and thereby detracting from the appearance and life of the instrument. Unlike prior writing instruments of this general type, the actuating mechanism is enclosed within an encompassing cap that effectively protects the operating mechanism.

2

Another and important object of the present invention is the provision of a novel clip assembly for a writing instrument, and novel means for spring-loading the clip and retaining it in operative position.

5 Further objects are to provide a construction of maximum simplicity, efficiency, economy and ease of assembly and operation, and such further objects, advantages and capabilities as will later more fully appear and are inherently possessed thereby.

10 In the drawing:

Figure 1 is a view in side elevation of a ball point pen or writing instrument embodying the present invention, the pen being shown approximately actual size and with the writing point exposed.

15 Fig. 2 is an enlarged view in vertical cross section longitudinally through the pen or writing instrument assembly of Fig. 1.

Fig. 3 is a fragmentary and further enlarged view in horizontal cross section taken in a plane represented by the line 3—3 of Fig. 2 and viewed in the direction of the arrows.

20 Fig. 4 is a view in vertical cross section taken in a plane represented by the line 4—4 of Fig. 2 and viewed in the direction of the arrows.

25 Fig. 5 is a view in vertical cross section taken in a plane represented by the line 5—5 of Fig. 2 and viewed in the direction of the arrows.

Fig. 6 is a view in vertical cross section taken on the irregular line 6—6 of Fig. 2 and viewed in the direction of the arrows.

30 Fig. 7 is a fragmentary top plan view of the cap and clip end of the pen or writing instrument.

Fig. 8 is an enlarged plan view of the plunger for propelling the cartridge and its point to writing position.

35 Fig. 9 is an enlarged plan view of the spring latch for latching and retaining the cartridge in writing position with the ball or writing point exposed.

Referring to the disclosure in the drawing and more particularly to the illustrative embodiment therein shown, the novel ball point pen or writing instrument comprises a barrel or hollow member 10 adapted to receive a retractable and replaceable unit or cartridge 11 including a ball or writing point 12 at its outer or forward reduced end and a tubular ink receptacle or reservoir 13 provided with an ink feed tube 14 at its outer end for supplying ink or writing fluid to the ball or writing point 12. As clearly disclosed in Fig. 2, the forward end of the tubular ink reservoir 13 is reduced to form the ink feed tube 14 and the latter is tapered at its extreme forward end to receive and seat the ball or writing point 12.

40 The barrel 10 is preferably formed of a plastic or other composition suitable for the purpose, and at its forward end is tapered to form a writing tip 15 provided with a reduced bore having spaced shoulders 16 and 17, the shoulder 17 adapted to receive the complementary shoulder or reduction 18 on the ink feed tube 14. The shoulder 16 is adapted to provide a seat for one end of a coil spring 19, the other end of this spring seating against spaced lugs or embossments 21 on an intermediate portion of the ink reservoir 13 of the cartridge 11 for spring-biasing this cartridge unit and its ball or writing point 12 to retracted position with the latter confined within the writing tip 15 of the barrel 10 until ready for use.

45 Secured to the upper, interiorly threaded end 22 of the barrel is a plug 23 having an exteriorly threaded reduction 24 adapted to be detachably secured to the barrel and recessed at 25 to receive the upper or inner end of the tubular ink reservoir 13 of the cartridge 11. This plug is provided with a transverse wall 26 slotted to receive the reduced outer or forward end 27 of a relatively flat and elongated plunger 28. This plunger is of such length as to extend from the position shown in Figs. 2

and 3 where the forward end 27 thereof abuts the upper or inner end of the cartridge 11, to the interior of the upper closed end of a cap shell 29 where the bifurcated upper end 31 of the plunger seats conformably in the cap shell. Intermediate the bifurcated end 31 with its longitudinal slot 32 and the reduced outer or lower end 27 (Fig. 8), the plunger is provided with a substantially rectangular and laterally disposed slot 33 opening into the longitudinally extending slot 32, oppositely disposed shoulders or offsets 34, an elongated, longitudinally extending slot 35 having a reduction at 36 at its forward end, oppositely disposed shoulders or offsets 37 and substantially rectangular slots 38 and 39 spaced apart to receive the depending ends or projections 41 and 42, respectively, of a release bar 43 (Figs. 2 and 3) carried and movable in a longitudinally extending slot 44 (Fig. 6) in the plug 23.

The plug 23 is also longitudinally slotted at 45 (Figs. 2, 3, 5 and 6) to receive the plunger 28 and a spring latch 46 (Fig. 9), the latter held adjacent its rear end against longitudinal movement by a pin 47 passing through an opening 48 in the latch and with its ends located in a transverse bore or opening 49 in the plug 23. The spring latch 46 is offset at the rear at 51 where it is adapted to seat and locate against the rear end of the recess 35 as well as against the sides of the cavity or slot 45 in the plug 23, and also reduced and inclined or offset at the forward end at 52 to seat against the forward end of the slot 39 when the ball point is extended for writing and thereby latching and retaining the plunger 28 in the extended position of Figs. 2 and 3. In this position (Fig. 2), the inclined end 52 is disposed adjacent an inclined or cam surface 53 on the depending end or projection 42 of the release bar 43, whereby depressing the button or protuberance 54 on the release bar 43 which projects through a slot in the cap shell 29 depressed the forward or inclined end 52 of the spring latch and permits the coil spring 19 to retract the cartridge 11 and move the plunger 28, the release bar 43 and the cap shell 29 longitudinally to their retracted or elevated position. Such movement is permitted by reason of the arrangement and contour of the slots in the plunger 28 and the arrangement and contour of the slots in the plug 23, the limit of movement being determined by the pin 47 reaching the forward end of the slot 36.

Mounted in the closed end of the cap shell 29 is a clamp member 55 having a substantially cup-shaped base 56 provided with a rearwardly tapered projection 57 the reduced end or lip 58 of which is bent outwardly to extend through a longitudinally extending slot 59 in the cap shell 29 aligned therewith and, when assembled, this reduced end or lip is bent over and onto the cap shell at the lower or forward end of the slot as shown in Fig. 2. Spaced approximately 180° from the projection 57, the clamp member is provided with inwardly projecting, elongated and spaced flanges 61 adapted to provide a longitudinally extending channel or housing for receiving and retaining there-between a coil spring 62, the lower or inner end of which spring seats against or abuts the base 56 and the upper or outer end of this spring bears against a shoulder 63 on the pivotally mounted or fulcrumed end 64 of a rigid pocket clip 65.

When the clamp member 55 is mounted in the assembled position shown, a projection 60 on each flange 61 is adapted to be received in the opposite ends of the transverse or laterally disposed slot 33 in the plunger 28, whereby these parts are connected in assembled relation.

To mount this rigid pocket clip 65 in the upper end of the cap shell 29 and associated with the clamp member 55, the upper end 64 of the clip is contoured to be received in the longitudinally extending slot 59 in the cap shell, and is provided with a notch or recess at 66 adapted to conformably receive the edge 67 of the cap shell at the upper or rear end of the slot 59 and fulcrum about this edge as the rounded free or engaging end 68 on the

shank 69 of the clip 65 is moved toward or away from the cap shell. As will be evident from Fig. 2, when the end or lip 58 projects through the slot 59 and is bent onto the cap 29, the enlarged end 64 of the clip is locked in the cap.

The drawing shows the cartridge 11 and its ball or writing point 12 moved to extended or writing position in which the coil spring 19 is held under compression. In this extended position, the cap shell 29, the clip 65, the plunger 28 and the release bar 43 all of which are slidably movable as a unit, have been moved or propelled to their lowered or extended position by the operator merely pushing downwardly or forwardly on the cap shell.

To release the plunger 28 and associated parts and permit retraction of the cartridge 11 and its ball or writing point 12 into the barrel of the holder, the button or protuberance 54 on the release bar 43 is depressed by pressing downwardly or inwardly on the free end 68 of the clip 65, whereby to depress the release bar and cause its depending ends 41 and 42 to in turn engage and depress the forward end of the spring latch 46. This disengages or removes the inclined or offset latching part 52 of the spring latch 46 from the slot 39 and releases it from latching engagement with the plunger 28.

Upon such disengagement or release, the spring 19 automatically retracts the cartridge 11 and its writing point 12 into the barrel 10, and the cartridge through its engagement with the plunger 28 forces the latter rearwardly over the spring latch 46 and carries therewith the cap shell 29, the clip 65, the clamp member 55 and the release bar 43 to their retracted position. To again move or propel the cartridge 11 and its writing point 12 to writing position from this retracted position, only downward or forward movement of the cap shell 29 relative to the plug 23 and barrel 10 forming the holder of the writing instrument, is required.

By merely unscrewing the barrel 10 from the plug 23, the holder is disassembled and access is readily had to the cartridge 11 for removal or replacement. The holder comprising the barrel and the plug are preferably formed of a suitable plastic composition and the remainder of any suitable metal, although any available material suitable for the purpose may be employed.

Having thus disclosed the invention, we claim:

1. A writing instrument comprising a hollow barrel provided with a reduced opening at its forward end, a cap having one end encompassing the other end of and longitudinally movable on the barrel, a cartridge slidably mounted in the barrel and provided with a writing point at its forward end adapted to be projected or retracted through said reduced opening, a slotted plug carried by said cap and at its forward end provided with a threaded reduction to which the upper end of said barrel is detachably mounted for removal of said barrel and replacement of the cartridge, resilient means in the barrel for urging and spring-biasing the cartridge toward retracted position with the writing point retracted through said opening, actuating means in said plug for projecting the cartridge and its writing point through said opening to writing position and including a slotted plunger longitudinally slidable and guided in the plug and at its forward end engaging the cartridge and its rear end engaging the interior of the cap, said cap when depressed moving said plunger in the plug to propel the cartridge and its writing point to writing position, a spring latch having a projection adapted to be received in the slot in the plunger for retaining said plunger in its propelled position, and a release bar having a protuberance projecting through an opening in the cap adapted to be depressed and a part extending into the slot of the plunger and engaging the projection on the spring latch for depressing and releasing said projection on the spring latch and thereby releasing the plunger whereupon said resilient means retracts said cartridge and its writing point.

2. A writing instrument comprising a barrel having a reduced opening at its forward end and internally threaded at the other, a cap having one end encompassing the other end of and longitudinally movable on the barrel, a cartridge slidably mounted in the barrel and provided with a writing point at its forward end adapted to be projected or retracted through said reduced opening, a hollow member carried by the cap and detachably mounted on the barrel for complete removal of the barrel and its contained cartridge, resilient means for urging and spring-biasing the cartridge toward retracted position in the barrel with the writing point retracted through said opening, actuating means for projecting the cartridge and its writing point through said opening to writing position and including a slotted plunger longitudinally slideable and guided in said member for moving the cartridge to projected position, said cap moving said plunger in said member to propel the cartridge and its writing point to writing position, a spring latch member having its ends received in spaced slots in the plunger with one of said ends releasably retaining the plunger and the cartridge in propelled position for writing, a clip on said cap and released means engaged by a part on said clip and actuated by movement of said clip for engaging and releasing said one end of the latch member from its slot in the plunger whereupon said resilient means retracts said cartridge and its writing point.

3. A writing instrument comprising a holder having a barrel provided with a writing tip and a reduced opening at its forward end and a slotted plug detachably mounted on the other end of the barrel, a cap carrying therein said slotted plug and encompassing the rear end of and longitudinally movable on said barrel, a cartridge slidably mounted in the barrel and provided with a writing point at its forward end adapted to be projected or retracted through said reduced opening of the barrel, resilient means for urging and spring-biasing the cartridge toward retracted position with the writing point retracted through said opening, a slotted plunger having an end engaging the cartridge and its other end engaged by the interior of the cap, said plunger being slidably mounted in the plug and actuated by movement of the cap to propel the cartridge and project its writing point through said opening to writing position, a spring latch bar having a part received in the slot of the plunger for releasably retaining the plunger and the cartridge in propelled position, a clip fulcrumed on said cap, and release means carried in the slot in the plug and having a part projecting through an opening in the barrel and in alignment with the clip and actuated by movement of the clip and a part projecting into the slot of the plunger for releasing the part on said latch bar engaging the plunger to release said plunger whereupon said resilient means retracts the cartridge and its writing point through the opening.

4. A ball point writing instrument comprising a slotted holder, a barrel detachably mounted on one end of said holder and provided with a longitudinal bore open at its forward end, a cartridge in said barrel having an ink reservoir and a ball writing point at its forward end adapted to be projected and retracted through the adjacent forward end of the barrel, a cap encompassing and slidably mounted on the other end of said holder, a longitudinally extending bar longitudinally movable in a slot of said holder and with said cap and provided with spaced slots, said bar engaging the inner end of said cartridge for moving the latter to projected position upon movement of the cap toward the forward end of the holder and the barrel, a spring latch member disposed along the bar with its opposite ends bent and adapted to be received in the spaced slots in said bar and with one end 70 of said latch member providing a latching end received in one of the slots of said bar for retaining the latter in projected position, a release bar having a projection also received in said one slot in the longitudinally extending bar adjacent the latching end of the latch member and 75

adapted to depress and release the latching end of said latch member when depressed and a spring for retracting the cartridge, longitudinally extending bar and cap when the latch member is released.

5. A ball point writing instrument comprising a slotted holder, a barrel detachably mounted on one end of said holder and provided with a longitudinal bore open at its forward end, a cartridge in said barrel having an ink reservoir and a ball writing point at its forward end adapted to be projected and retracted through the adjacent forward end of the barrel, an actuating cap encompassing and longitudinally movable on the other end of the holder, an elongated bar mounted for reciprocation in the slot of said holder and at one end engaging the cartridge and at its other end engaged by the interior upper end of said cap whereby movement of the cap is communicated to said bar and cartridge, a slot in said bar, a spring latch member disposed alongside said bar and provided with a spring latch element spring-biased into said slot and thereat retaining said bar and cartridge in projected position, a release member carried by said cap and slidably mounted in a slot in said holder, said released member having a part received in said slot of said latch member and engaging said latch element and a part projecting through and to the exterior of the cap and adapted to be depressed to release the latch element of said latch member and permit retraction of said bar and cartridge, and means for retracting said bar and cartridge upon release of the latch member.

6. A writing instrument comprising a slotted holder, a barrel open at its forward end and detachably connected at its rear to the holder, a writing unit in said barrel having a writing point at its forward end adapted to be extended or withdrawn through the adjacent forward end of the barrel, a cap member encompassing and longitudinally movable on said holder and the rear end of the barrel, an elongated, reciprocable plunger bar in said holder having one end engaging the cartridge and at its other end engaged by the interior of the cap whereby movement of the cap is communicated to said plunger and by it to the cartridge, said plunger bar having a slot intermediate its ends, a spring latch member having a resilient latching end adapted to be spring-biased into spring latching engagement in the slot of the plunger bar and retaining the plunger in extended position, a release bar longitudinally movable in the slot of said holder and movable with said cap and having a part received in the slot of said plunger bar and thereat engaging said latching end and a part projecting to the exterior of the cap and adapted to be depressed to release the latching end of said latch member and permit retraction of said plunger and cartridge, means for retracting said cartridge and plunger upon release of the latch member, and a clip pivotally mounted in said cap for engaging the projecting part of said release bar to release the plunger, said part on the release bar projecting to the exterior of the cap being so disposed as to be automatically depressed when the pen is returned to the pocket to be retained therein by the clip.
